UNITED STATES PATENT OFFICE.

HERMANN WINTER, OF NEW YORK, N. Y., ASSIGNOR, BY MESNE ASSIGNMENTS, TO F. WESEL MANUFACTURING COMPANY, OF BROOKLYN, NEW YORK, A CORPORATION OF NEW YORK, (INCORPORATED 1906.)

DRILLING AND NAILING MACHINE.

No. 879,347.

Specification of Letters Patent.

Patented Feb. 18, 1908.

Application filed April 10, 1905. Serial No. 254,699.

To all whom it may concern:

Be it known that I, HERMANN WINTER, of the borough of Brooklyn, of the city of New York, in the State of New York, have invented certain new and useful Improvements in Drilling and Nailing Machines, of which the following is the specification, reference being had to the accompanying drawings, forming part hereof.

10 In such apparatuses as drilling and nailing machines for attaching electrotype plates, zinc etchings &c. to wooden blocks, and for various other purposes, it is always desirable that the machine shall stop after each complete cycle of operation, so that the work in the machine may be properly adjusted. For this purpose, these machines and machines of like general character are provided with a clutch arrangement to stop the machines at 15 the proper time, which clutch arrangement is under the immediate control of the operator who, when he has adjusted the work, starts up the machine again.

In drilling and nailing machines, it is particularly desirable, with some kinds of work, that drill spindles shall have ample time to drill a hole of sufficient extent to permit relatively long nails to be used.

It is therefore the object of this invention 30 to provide a clutch which shall be capable of operating automatically in machines of this sort to permit the drilling to continue while the rest of the machine is at rest, and to start the machine again at a predetermined 35 time that is, when the drill shall have completed a hole sufficiently large for the purpose in hand.

In the drawings, a drilling and nailing machine, in which the clutch improvements 40 may be embodied, is sufficiently illustrated to enable the application of the improvements to be understood, and the improvements are also illustrated in detail.

In said drawings, Figure 1 is a side elevation of the drilling and nailing machine, Fig. 2 is a front elevation of the same, Fig. 3 is a detailed sectional view of a portion of the machine on a larger scale taken on the plane indicated by the line 3—3 in Fig. 2, Fig. 4 is 50 a view partly in elevation and partly in section of a portion of the machine showing the application of the clutch thereto and its position adjacent to the driving pulley therein. Figs. 5 and 6 are views in elevation of the

side of the clutch casing next the driving 55 pulley, showing respectively two positions of the clutch parts. Fig. 7 is a detailed sectional view and Figs. 8 and 9 are detailed views in perspective showing parts of the clutch mechanism to be referred to more particularly hereinafter.

It will be necessary, for purposes of this description, to refer very briefly only to the general character of the machine illustrated in the drawings, in order to enable the application of the improved clutch thereto to be readily understood. For the details of construction of such machine, reference can be had to Letters Patent of the United States No. 791,287, dated May 30, 1905.

The work is supported on a suitable table 13 which surmounts a stand 12, the latter being ordinarily just high enough to bring the work into a convenient position for manipulation by the operator while standing up. 70 Directly over the work and mounted side by side are the drill, and its spindle 30, part of the nail delivering mechanism 58, 74, 75, and the hammer 86. The spindle, hammer and the parts of the nail delivery mechanism referred to are carried by a reciprocating plate 15, which has flanged portions 16 and 17 overhanging respectively the upper and lower portions of the end 14^a of a standard or support 14 which rises from the stand 12. 85 By this means and through the operation of a crank pin 22 on the shaft 20, as is afterwards explained, the spindle with its drill and the hammer and nail delivering mechanism are shifted, so that the spindle after drilling a 90 hole may be moved laterally and the block 75, through which the nails are delivered and through which the hammer drives, may be brought over the hole drilled by the spindle. The spindle is driven through a belt 33 engaging its pulley 34, which belt passes around guide pulleys 35 and thence down around a pulley 36 on the lower part of the stand and is lowered and raised between successive shifting of the carrier, so as to rest down upon 100 the work and then be raised above the work, for an arm 42 of a bell crank 40 under the control of pin 22. The carrier 15, however, is reciprocated and the hammer and nail feeding mechanism is actuated through a 105 main shaft 20 which has its bearing in the horizontal member of the standard 14, and to which the driving pulley 23 is secured.

The carrier may be reciprocated by means of a crank pin 22, rotated by the main shaft, engaging the walls of an irregular slot 26 in said carrier. The nails which slide down from a magazine 50 along an inclined track 51 are fed one by one into the tube 74 by a tubular block 57 having a hooked portion, the tubular block being oscillated by the reciprocation of the carrier plate. The hammer 10 is driven by an arm 87 (Fig. 3) to which it is secured, said arm projecting forward from a reciprocating plate 88 sliding in a channel in the rear face of the carrier plate 15. Said plate 88 is reciprocated by the crank arm 22 15 engaging a slot in the same. These several mechanisms are preferably timed, so that one revolution of the shaft 20 effects the shifting of the carrier 15 to bring the nail delivering mechanism and hammer into proper position, 20 the operation of the nail delivering mechanism and hammer and the returning of the carrier plate to its first position, that is just one cycle of operations. In order that the mechanism may come to a stand-still after 25 each complete cycle of operations, so that the work may be re-arranged in the machine (and by mechanism the drill spindle is not necessarily included), a clutch is provided for the main shaft 20 and may be controlled from a 30 foot lever 24 through the medium of a connecting rod 25.

The clutch is preferably constructed to permit the shaft 20 and all the operative parts of the machine controlled through the 35 shaft 20 to rest for a predetermined time after the spindle is brought down upon the work, while the drill spindle is continued in rotation through the belt 33 and the pulleys 34, 35 and 36, all as heretofore explained. 40 This, as will be obvious, will allow the spindle to be operated to perform its drilling while all the other operative parts of the machine are for the time being stopped. For this purpose, one of the members of the clutch 45 may consist of a driving pin 90 secured in any suitable manner to the driving pulley, the driving pulley in this case together with the pin 90, constituting the driving member of the machine; while the other member of 50 the clutch is preferably contained in a collar 91, which is made fast, by any suitable means, to the driven member or shaft 20. Within this collar and constituting a part of the clutch are two keys 92 and 93 respectively, the latter of which is somewhat longer 55 than the former and both of which are normally urged outward from the collar into the range of the driving member or pin 90 by suitable means such as springs 94 acting 60 against pins 95 on the keys. The inner ends of the keys are hooked, as shown, and at certain points in the revolution of the shaft 20 engage with means such as cams 96, 97 and 98 respectively, whereby they are drawn out 65 of the range of pin 90 and are so held until

they have passed these cams. These releasing cams are preferably constructed as shown in Figs. 7, 8 and 9, the cams 96 and 97 being exactly alike while the cam 98 is as much thicker than the cams 96 and 97, or in other words its extreme rise is as much higher than the corresponding rise in cams 96 and 97, as the pin 93 is longer than the pin 92. In this way as the key 93 passes the cams 96 and 97 it will not be drawn completely into 70 the collar 91 and hence it will not be drawn completely out of the range of the pin 90, while the key 92 in passing any of the cams will be drawn out of engagement with the pin 90. 75

In order to effect the desired timing of the operation of the drill with respect to the operation of the rest of the machine, the keys 92 and 93 are placed substantially 90 degrees apart, and the cams are also placed 80 substantially 90 degrees apart. Furthermore, the cams 97 and 98 are stationary while the cam 96 is connected with the foot lever 24 through the connecting rod 25, and the operation of the clutch is as follows: 85

With the parts in the position shown in Fig. 5, the foot lever is actuated, thus drawing cam 96 away from the key 92, the latter immediately projecting itself into the range of the continuously rotating pin 90, by which it is engaged and through which it causes the rotation of the shaft 20 in the direction of the arrow. As soon as the shaft has been turned through a quarter of a revolution, or substantially 90 degrees, the key 92 is brought into 95 engagement with the cam 97 which draws the key back into the collar 91 out of the range of the pin 90 and permits the pulley 23 with the driving pin, to continue rotating while the shaft and all the operative parts which it 100 controls are at rest. The key 93, however, which, when the shaft commenced to move, was in engagement with the cam 98 and was thus drawn completely out of the range of the pin 90, has been brought by the first quarter 105 revolution of the shaft 20 opposite the cam 96, and in engagement therewith. The cam 96, however, is not thick enough to withdraw the key 93 wholly from the range of the pin 90 and accordingly the pin 90, after leaving 110 key 92 will revolve about three-quarters of a revolution until it engages (Fig. 6) the pin 93. This engagement then effects a further rotation of shaft 20 through about three-quarters of a revolution, when the key 93 will 115 be engaged again by cam 98 and completely withdrawn from the range of pin 90. This, as is obvious, will bring the clutch parts to their initial position, shown in Fig. 5, in which they will remain until the foot lever 24 120 is again operated. It will be seen therefore that when the crank pin has moved through about 90 degrees, which involves substantially a quarter of a revolution of the shaft, all the operative parts of the machine except 125 130

the drill spindle will become motionless until the driving pulley has moved through a further three-quarters of a revolution or thereabouts. During this three-quarters of a revolution, the drill spindle being driven directly or continuously from the driving pulley, that is not through the medium of a clutch but through belt 33, and pulleys 34, 35 and 36, is in operation. At the completion of this three-quarters of a revolution of the driving pulley, during which the shaft 20 is at rest, the clutch mechanism will be operated and through the operation of said mechanism the rest of the machine will be started and will continue in operation until the shaft 20 is rotated through three-quarters of a revolution, thus making one complete revolution of the shaft 20 and thus completing one cycle of operations of the parts controlled through said shaft.

It will be understood, that, as in all clutches, it is immaterial which member of the clutch is secured to the driving member and which member of the clutch is secured to the driven member and accordingly, although for purposes of convenience in construction the clutch collar 91 is shown connected to the driven member, it will be obvious that the invention is not limited to this particular construction.

I claim as my invention:

1. In a drilling and nailing machine, the combination with a drill, of a driving member directly connected to drive said drill, a mechanism to move said drill laterally, and a clutch to operate said moving mechanism, said clutch including means substantially as described to operate said moving mechanism to bring the drill into position for drilling to allow it to remain in such operative position a predetermined time and permit it to return to its normal position.

2. In a drilling and nailing machine, the combination with a drill, of a driving mem-

ber, directly connected to drive said drill, a carrier for said drill, a lever for moving the drill into and out of operative position, and a clutch to operate said carrier and lever, said clutch including means substantially as described to operate said carrier and lever to bring the drill laterally into position for drilling, allowing it to remain in such operative position a predetermined time and to return it to its normal position.

3. In a drilling and nailing machine the combination with a drill, of a driving member, directly connected to drive said drill, mechanism for supporting and operating said drill, a clutch to operate said mechanism, said clutch including means substantially as described to operate mechanism to bring the drill laterally into position for drilling, allowing it to remain in such operative position a predetermined time and to permit it to return to its normal position, and means for initially engaging said clutch and driving member.

4. In a drilling and nailing machine, the combination with a drill, of a driving member, a carrier and lever for moving the drill into and out of operative position, and a clutch to operate said carrier and lever, said clutch having two keys adapted to engage the driving member, and means for initially engaging the clutch with the driving member, whereby when a clutch is once engaged it will automatically operate to bring the drill laterally into position for drilling, allowing it to remain a predetermined time and restore it to its normal position in a single cycle of operation.

This specification signed and witnessed this 14th day of March A. D., 1905.

HERMANN WINTER.
